UNITED STATES PATENT OFFICE.

CHARLES L. CADLE, OF ROCHESTER, NEW YORK, ASSIGNOR TO THE ELECTRIC RAILWAY IMPROVEMENT COMPANY, OF CLEVELAND, OHIO, A CORPORATION OF OHIO.

CONVERTER.

1,129,330.

Specification of Letters Patent.

Patented Feb. 23, 1915.

Application filed December 18, 1911. Serial No. 666,425.

To all whom it may concern:

Be it known that I, CHARLES L. CADLE, of Rochester, in the county of Monroe and State of New York, have invented certain 5 new and useful Improvements in Converters; and I do hereby declare the following to be a full, clear, and exact description of the same, reference being had to the accompanying drawings, forming a part of this 10 specification, and to the reference-numerals marked thereon.

My invention relates to converters, particularly of the type designed for changing a direct electric current to an alternating 15 electric current such as is employed for railway and lighting systems, and it has for its object to provide means for breaking a circuit of heavy potential in such a manner that no arc will be formed of sufficient magnitude 20 to effect any noticeable destructive action on the commutating segments.

My invention further consists in dividing the current as it passes through the commutator so that an arc cannot be formed on any 25 single commutator segment to a sufficient extent to destroy an appreciable amount of the metal forming the commutating segment.

Another object of my invention is to provide means whereby the total amount of 30 current will not be interrupted at a single instant as by interposing suitable resistance in the circuit.

To these and other ends the invention consists in certain improvements and combinations of parts, all as will be hereinafter more 35 fully described, the novel features being pointed out in the claims at the end of the specification.

In the drawing: Figure 1 is a view in elevation of a converter embodying a preferred 40 form of my invention, and showing the arrangement of the direct and alternating current circuits with respect thereto; Fig. 2 is a sectional view on the line $x-x$ of Fig. 1, 45 and Fig. 3 is a diagrammatic view of the commutator, showing the arrangement of circuits, the commutating segments, and the resistance elements interposed in the circuit.

My invention is designed primarily for 50 producing alternating current from direct current by an improved method, being applicable for forming either a single phase or a polyphase circuit, and in the present embodiment, I have illustrated the invention 55 by an arrangement adapted to form a single

phase circuit, A designating the incoming, or direct current circuit, and B the outgoing or alternating current circuit, which is connected as shown, to the brushes 2. The direct current circuit is connected to the brushes 3, 60 while 4 designates brushes arranged about the commutator and connected together in pairs, as by the wires 5, the brushes 4 co-operating with parts of the commutator in a manner that will now be described. 65

The commutator is preferably in the form of a rotating cylinder, designated by 6, and adapted to be actuated by a suitable motor or other desirable means. Commutating rings 7 are provided which co-operate with the brushes 2. Arranged for co-operation with the brushes 3 and 4 are the commutating segments 8 and spaced therefrom at slight distances are smaller commutating segments 9 which are connected with the segments 8 by means of the resistances 10 for a purpose that will presently appear. The commutating segments are separated by insulated sections in a manner that is well known in the art, and need not be described. 75 It will be noted that the contacting surfaces of each brush is slightly wider than the distance between the sides of the segments which are connected by resistances, and slightly narrower than the distance between the opposite sides of the segments, and this permits the brushes to bridge the segments 8 and 9 as the commutator rotates, whereupon the resistance elements are brought into the circuit so that when the segments 9 pass away 80 from contact with the brushes, the total current is not interrupted at a single instant, thus obviating any action on the commutator that might be set up by an inductive load. 85

In order to divide the current in such proportions that it will not form an arc on any one segment large enough to affect the metal to an appreciable extent, I preferably provide a double number of sets of commutating segments, as shown, the circuits being arranged to permit the current to pass through said segments in parallel, and to this end, the direct current circuit is divided, forming the leads 11 and 12 respectively, the circuits 90 formed thereby being connected with the commutating rings 7 by means of wires 13 and 14, respectively. It will be understood 100 that the dividing of the current in the manner just described, while constituting an im- 105

portant feature of my invention, is not indispensable to the remaining parts, which include the means for breaking the circuits at a plurality of points, at a single instant, and interposing resistance elements in the circuit for the purposes already mentioned.

I claim as my invention:

1. The combination with direct and alternating current circuits, of a rotary commutator connecting the circuits and embodying means for dividing the current, means for breaking the divided circuit at a plurality of points simultaneously including a series of comparatively large commutating segments, and a corresponding number of comparatively small commutating segments arranged in spaced relation to the larger segments, and resistance elements connecting the segments.
2. The combination with direct and alternating circuits, of a commutator connecting the circuits, said commutator embodying

means for dividing the current while passing from one of said circuits to the other, means for breaking the divided circuit at a plurality of points simultaneously, and resistance elements adapted to be introduced into the respective divisions of such divided circuit incidentally to the breaking of the same.

3. The combination with direct and alternating circuits, of a rotary commutator connecting the circuits and embodying means for dividing the current, means for breaking the divided circuit at a plurality of points simultaneously including two series of commutating segments arranged in spaced relation to each other, and resistance elements connecting corresponding segments of said two series.

CHARLES L. CADLE.
